UNITED STATES PATENT OFFICE

2,093,617

PORTABLE CRANE BASE

Elon A. Ormsby, Centerville, Calif.

Application December 22, 1936, Serial No. 117,226

1. Claim. (Cl. 212—69)

This invention is an improvement on the portable folding crane shown in my United States Patent No. 2,023,790, dated December 10, 1935.

The object of the present invention is to improve the construction of said crane, with respect particularly to the means for supporting its post and other parts, in such manner that it can be readily turned or swung from side to side, while being supported in upright position when 10 in operation.

The invention is illustrated in the accompanying drawing in which:—

Fig. 1 is a perspective view showing the improvement.

Fig. 2 is a plan view of the base, the other parts of the crane being removed.

Fig. 3 is a perspective view of a channeled track on which the swinging part of the base turns.

As shown in said patent the crane includes a 20 post 6, a pivoted boom 7, a hoisting cable 8, a chain 9 connecting the base to the rear end of the boom, and a gear box 10 containing a crank and other parts operated by the crank handle 11 to wind up the cable which passes over suitable guide rollers 12, one of which is mounted in the 25 lower end of the post 6. These parts are substantially as shown in said patent and need not be more particularly described.

The base consists of a segmental frame 13 cast 30 with a central hub 14 which rests on ball bearings (not shown) between said hub or center plate and a suitable bearing plate 15 fixed to the platform or truck on which the crane is mounted. Said platform or truck may be of any 35 suitable construction and is indicated at 16.

The lower end of the post 6 sets between the ears 17 of a U-shaped bracket which has an axle 40 extending through the hub and the bearing members, forming a pivot on which the frame turns with the post.

At its periphery or outer end the frame 13 is provided with a plurality of rollers 18 mounted on studs or pins projecting from the end of the frame. These rollers travel in a track casting

19, arcuate in form, and having upper and lower flanges 20 and 21 forming retaining guides for the rollers. The track casting is bolted to the platform as by bolts 22.

The frame is also provided with an arm 23 to which the lower end of the chain 9 is connected in any suitable way, as by a hook, the chain 9 serving to anchor the boom of the frame as described in said patent. Stop bolts 24 extend through the flanges at each end of the track, to 10 prevent the rollers running out.

The frame 13 also has ribs 26 with holes 27 to permit the connection of the lower ends of braces 28, the upper ends of which are bolted or otherwise fastened to the gear box 10, so as to 15 assist in supporting the post 6 in upright position.

When the post and other parts are mounted on the base described it can be turned or swung from side to side to swing the load accordingly. 20 This can be readily done because of the rollers and ball bearings at the friction points, and permits loads to be readily moved or swung to any desired position with very little effort.

As stated, the base will be found particularly 25 useful in the type of crane shown in the patent above referred to, but it may be used in other relations, within the scope of the invention.

I claim:

A base for a crane, comprising a platform, 30 an arcuate channeled trackway having upper and lower flanges, fixed to the platform, a center bearing plate fixed to the platform, a segmental casing having a hub resting on said bearing plate, a pivot extending through the hub and plate and 35 having a bracket at its upper end to support the center post of the crane, said casting also having a projecting arm for connection of a crane anchor and ribs for connection of braces for the center post, and a plurality of rollers at the 40 periphery of the casting, running between the flanges of the trackway.

ELON A. ORMSBY.
